his ATTORNEY.

UNITED STATES PATENT OFFICE.

GUSTAV WIEDEKE, OF DAYTON, OHIO, ASSIGNOR TO GUSTAV WIEDEKE COMPANY, OF DAYTON, OHIO, A FIRM.

TUBE AND FLUE EXPANDER.

Application filed November 29, 1926. Serial No. 151,383.

This invention relates to tube and flue expanders and while designed primarily for use in connection with boiler tubes and boiler flues it is not limited to such use and the 5 term "tube" as herein used is intended to include any tubular member to which the device may be applied.

One object of the invention is to provide a device of this kind which will automatically position the tube with relation to the tube sheet and which may be adjusted to cause the tube to extend the desired distance beyond the tube sheet.

A further object of the invention is to 15 provide such a device in which the tube positioning means will not interfere with the radial movement of the expanding rollers and a maximum expansion may be had.

A further object of the invention is to 20 provide such a device having cooperating adjustable members whereby the positions of the expanding rollers with relation to the tube sheet will be controlled and the position of the tube with relation to the tube 25 sheet may be controlled.

Other objects of the invention will appear as the device is described in detail.

In the accompanying drawings Fig. 1 is 30 a side elevation of a tube expander embodying my invention, with the mandrel partly broken away; Fig. 2 is a longitudinal sectional view of such a tube expander; Fig. 3 is a transverse sectional view taken on the line 3—3 of Fig. 2; Fig. 4 is a transverse sectional view taken on the line 4—4 of Fig. 2; and Fig. 5 is a sectional detail view showing one of the expanding rollers in its extended position.

In these drawings I have illustrated one 40 embodiment of my invention and have shown the same as applied to a boiler tube 10 mounted in a tube sheet 11. In that embodiment of the invention here illustrated the expander comprises a frame or body portion 12 the inner portion of which is adapted to extend into the tube which is to be expanded and is provided with a series of radial slots 13 in each of which is mounted a roller 14, these rollers being capable of 45 radial movement in the slots and being actuated by the usual tapered mandrel, which extends through a bore 16 extending for the full length of the frame. The slots preferably extend at a slight angle to the axis 50 of the frame for a purpose which will hereinafter appear.

55 The rollers may be confined within the slots in any suitable manner but, in the present instance, the slots are constricted at their outer edges, as shown at 17, to limit the outward movement of the rollers and a retaining device or cage is inserted in the inner portion of the bore to limit the inward movement of the rollers.

The inner portion of the bore 16 is enlarged to receive the retaining device which comprises a tubular end portion 18 seated in the inner end of the bore and having a series of fingers 19 extending lengthwise of the bore between the several rollers and spaced apart distances 60

less than the diameter of the rollers, as shown in Fig. 3, thus limiting the inward movement of the rollers when the mandrel has been withdrawn. The retaining device 65 is held in place by means of a screw 20. The outer portion of the frame 12 is of a reduced diameter and has mounted thereon a head 21 which is preferably adjustable axially of the frame and which, in the present instance, is screw threaded onto the reduced 70 portion or shank of the frame and is held normally against rotation thereon by means of a set screw 22 which extends into a longitudinal groove 23 in the outer threaded surface of the shank. The screw merely 75 serves to prevent the rotation of the head with relation to the shaft and is not subjected to any strain or thrust which may be imposed upon the head.

The inner portion of the head is of reduced diameter and is provided with a circumferential bearing surface 24. The enlarged outer portion of the head forms a shoulder 25 at the outer end of the bearing surface 24. Rotatably 80

mounted on the bearing surface 24 of the head is a collar 26 which is so arranged that its inner end will abut against the outer end of the tube 10. The outward axial movement of the collar 26 is limited by the shoulder 25 on the head and preferably a suitable 85 bearing is interposed between the shoulder and the outer end of the collar, this bearing being here shown as a plain bronze bearing 90

27. The collar is retained on the head by means of a set screw 28 extending through the same and seated in a groove 29 arranged circumferentially of the bearing surface 24. This groove is of such a width with relation 95

100 to the shoulder 25 that the screw 28 may be withdrawn without disengaging the shoulder 25 from the head 21.

105 The head 21 is provided with a longitudinal slot 30 which is of such a width that the screw 28 may be withdrawn without disengaging the shoulder 25 from the head 21.

110 The head 21 is provided with a longitudinal slot 30 which is of such a width that the screw 28 may be withdrawn without disengaging the shoulder 25 from the head 21.

115 The head 21 is provided with a longitudinal slot 30 which is of such a width that the screw 28 may be withdrawn without disengaging the shoulder 25 from the head 21.

120 The head 21 is provided with a longitudinal slot 30 which is of such a width that the screw 28 may be withdrawn without disengaging the shoulder 25 from the head 21.

125 The head 21 is provided with a longitudinal slot 30 which is of such a width that the screw 28 may be withdrawn without disengaging the shoulder 25 from the head 21.

130 The head 21 is provided with a longitudinal slot 30 which is of such a width that the screw 28 may be withdrawn without disengaging the shoulder 25 from the head 21.

135 The head 21 is provided with a longitudinal slot 30 which is of such a width that the screw 28 may be withdrawn without disengaging the shoulder 25 from the head 21.

to the set screw that the collar may have sufficient axial movement to cause it to abut against the bearing 27 and thus relieve the screw of all thrust or strain. Mounted on 5 and rigidly secured to the collar 26 is a guard 30 having inwardly projecting portions 31 arranged to engage the outer face of the tube sheet 11. This guard is adjustable with relation to the collar but is held 10 normally against all movement with relation thereto. Preferably the collar is provided with external screw threads and the guard with internal screw threads whereby the guard may be adjusted to various positions 15 with relation to the collar. The guard is retained in its adjusted positions on the collar by means of set screws 32 which extend into the longitudinal grooves 33 formed in the outer threaded surface of the collar, 20 the arrangement being such that the set screws will not be subjected to strain or wear, as all thrust will be imposed upon the threaded connection between the guard and the collar.

25 When a tube is to be expanded the guard 30 is first adjusted with relation to the collar 26 to cause the inner end of the guard to be spaced from the inner end of the collar a distance equal to the distance the tube is 30 to project beyond this tube sheet. The inner portion of the frame is then inserted in the tube and moved inwardly until the guard contacts with the tube sheet. If the end of the tube extends beyond the tube sheet a 35 greater distance than that for which the expander is set the contact of the collar with the end of the tube will cause the tube to be forced inwardly until the guard engages the tube sheet and the tube is in proper position.

40 The mandrel is then actuated in the usual manner to rotate the frame and force the expanding rollers radially outward. Because of the inclined positions of the rollers with relation to the axis of the frame these 45 rollers tend to draw the mandrel and the frame inwardly and the movement of the frame being limited by the contact of the guard with the tube sheet this action of the rollers will tend to move the tube outwardly.

50 Therefore, if the tube does not project the desired distance beyond the tube sheet it will automatically move outwardly until it contacts with the collar. The guard, collar and tube are held stationary and the frame 55 and head 21 rotate with relation thereto and this rotation of the frame and the gradual inward movement of the tapered mandrel causes the rollers to move outwardly to expand the tube, as shown in Fig. 3. The inner 60 corners of the rollers are curved about a relatively long radius, as shown at 34, thus causing a gradual expansion of the tube at the inner ends of the rollers and avoiding a sharp shoulder or break in the tube at this 65 point. The outer ends of the rollers have

substantially sharp corners which preferably extend substantially to the end of the tube so that the tube will be expanded to the full end thereof, thus avoiding the tendency of the tube to crack as will sometimes happen 70 if it is not expanded to the full end thereof. It will be noted that the inner end of the rotatable collar 26 lies just beyond the outer ends of the rollers so that the collar is out 75 of the paths of the rollers and will not in any way interfere with the radial movement thereof, thereby permitting the rollers to be moved to the full limit of their outward movement and a full expansion to be had, 80 the ends of the rollers overlapping the end of the collar when in their fully extended positions, as shown in Fig. 3. The present arrangement is such that the rollers may be expanded to a diameter substantially equal 85 to the diameter of the opening in the tube sheet in which the tube is mounted, thus enabling the expander to be used for the purpose of removing burrs from those openings. By adjusting the head 21 on the shank 90 of the frame the position of the expanding rollers with relation to the tube sheet may be controlled and by then adjusting the guard 30 with relation to the collar 26 the length of tube which projects beyond the 95 tube sheet may be controlled. The head 21 is reversible on the shank so that it may be mounted thereon with the enlarged portion thereof arranged in position to contact with the end of the tube, this being desirable under certain conditions.

100 While I have shown and described one embodiment of my invention I wish it to be understood that I do not desire to be limited to the details thereof as various modifications may occur to a person skilled in the art.

105 Having now fully described my invention, what I claim as new and desire to secure by Letters Patent, is:

1. In a device for expanding a tube in a tube sheet and comprising expanding rollers and a mandrel for actuating the same, a frame having slots to receive said rollers and having a longitudinal bore to receive said mandrel, a guard supported by and rotatable about the outer portion of said frame and arranged to engage the tube sheet, and means controlled by the normal operation of said device for positioning the tube with relation to the tube sheet, said means comprising a part adjustable with relation to 110 said guard to determine the position of said tube.
2. In a device for expanding a tube in a tube sheet and comprising expanding rollers and a mandrel for actuating the same, a frame having slots to receive said rollers and having a longitudinal bore to receive said mandrel, a guard supported by and rotatable about the outer portion of said frame and arranged to engage the tube sheet, and a 115
- 120
- 125
- 130

- part rigidly and adjustably connected with said guard, spaced from the inner end thereof and arranged to engage the end of the tube, said expanding rollers being arranged 5 to exert an outward pressure on said tube when they are actuated by said mandrel.
3. In a device for expanding a tube in a tube sheet and comprising expanding rollers and a mandrel for actuating the same, a frame having slots to receive said rollers and having a longitudinal bore to receive said mandrel, a tube engaging member supported by and rotatable about the outer portion of said frame, and a guard carried by 10 said tube engaging member and arranged to engage the tube sheet.
4. In a device for expanding a tube in a tube sheet and comprising expanding rollers and a mandrel for actuating the same, a frame having slots arranged at an angle to the axis thereof to receive said rollers and having a longitudinal bore to receive said mandrel, a tube engaging member supported by and rotatable about the outer portion of 15 said frame, and a guard adjustably mounted on said tube engaging member and arranged to engage said tube sheet.
5. In a device for expanding a tube in a tube sheet and comprising expanding rollers and a mandrel for actuating the same, a frame having slots arranged at an angle to the axis thereof to receive said rollers and having a longitudinal bore to receive said mandrel, a tube engaging member supported 20 by and rotatable about the outer portion of said frame, and a guard carried by and having screw threaded engagement with the tube engaging member, and means for holding said guard and said tube engaging member normally against relative movement.
6. In a device for expanding a tube in a tube sheet and comprising expanding rollers and a mandrel for actuating the same, a frame having slots to receive said rollers and having a longitudinal bore to receive 25 said mandrel, said frame having near its outer end a part having a circumferential bearing surface, a collar rotatably mounted on said bearing surface and arranged to engage the end of a tube, and a guard secured to said collar and arranged to engage the tube sheet.
7. In a device for expanding a tube in a tube sheet and comprising expanding rollers and a mandrel for actuating the same, a frame having slots to receive said rollers and having a longitudinal bore to receive 30 said mandrel, said frame having near its outer end a part having a circumferential bearing surface, a collar rotatably mounted on said bearing surface and arranged to engage the end of the tube, and a guard rigidly but adjustably mounted on said collar and arranged to engage said tube sheet.
8. In a device for expanding a tube in a tube sheet and comprising expanding rollers and a mandrel for actuating the same, a frame having slots to receive said rollers and having a longitudinal bore to receive 35 said mandrel, a head carried by the outer portion of said frame and having a circumferential bearing surface, a collar rotatably mounted on said bearing surface and arranged to engage the end of said tube, said head also having a shoulder to limit the axial movement of said collar in one direction, and a guard carried by said collar and arranged to engage said tube sheet.
9. In a device for expanding a tube in a tube sheet and comprising expanding rollers and a mandrel for actuating the same, a frame having slots to receive said rollers and having a longitudinal bore to receive 40 said mandrel, a head carried by the outer portion of said frame and having a circumferential bearing surface, a collar rotatably mounted on said bearing surface and arranged to engage the end of said tube, said head also having a shoulder to limit the axial movement of said collar in one direction, and a guard carried by said collar and arranged to engage said tube sheet, said guard being adjustable axially of said collar to vary the distance between said collar and said tube sheet.
10. In a device for expanding a tube in a tube sheet and comprising expanding rollers and a mandrel for actuating the same, a frame having slots to receive said rollers and having a longitudinal bore to receive 45 said mandrel, a head carried by the outer portion of said frame and having a circumferential bearing surface, a collar rotatably mounted on said bearing surface and arranged to engage the end of said tube, and having external screw threads, a guard having internal screw threads to cooperate with the threads on said collar and arranged to engage said tube sheet, and a thrust bearing carried by said head and engaging the outer end of said collar.
11. In a device for expanding a tube in a tube sheet and comprising expanding rollers and a mandrel for actuating the same, a frame having slots to receive said rollers and having a longitudinal bore to receive 50 said mandrel, a head carried by the outer portion of said frame and having its outer portion of greater diameter than its inner portion to form a shoulder thereon, the inner portion of said head having a circumferential groove, a collar rotatably mounted on the inner portion of said head and arranged to engage the end of the tube, a screw mounted in said collar and extending into said groove, a bearing interposed between said collar and the shoulder on said head, and a guard rigidly but adjustably mounted on 55 said collar and arranged to engage the tube sheet.

12. In a device for expanding a tube in a tube sheet and comprising expanding rollers and a mandrel for actuating the same, a frame having slots to receive said rollers and having a longitudinal bore to receive said mandrel, a head carried by the outer portion of said frame and having its outer portion of greater diameter than its inner portion to form a shoulder thereon, the inner portion of said head having a circumferential groove, a collar rotatably mounted on the inner portion of said head and arranged to engage the end of the tube, a screw mounted in said collar and extending into said groove, a bearing interposed between said collar and the shoulder on said head, said collar having external screw threads and having a longitudinal groove in the threaded surface thereof, a guard screw threaded onto said collar and arranged to engage the tube sheet, and a set screw mounted in said guard and extending into the groove in said collar to hold said guard in its adjusted position with relation to said collar.
13. In a device for expanding a tube in a tube sheet and comprising expanding rollers and a mandrel for actuating the same, a frame having slots to receive said rollers and having a longitudinal bore to receive said mandrel, a head carried by the outer portion of said frame and having a circumferential bearing portion, a collar rotatably mounted on the circumferential bearing portion of said head and arranged to engage
- the end of the tube, the inner end of said collar being arranged adjacent to the ends of the slots in said frame to permit the ends of the rollers to pass the same when the latter are moved radially, a thrust bearing carried by said head to limit the outward movement of said collar, and a guard adjustably mounted on said collar and arranged to engage the tube sheet.
14. In a device for expanding a tube in a tube sheet and comprising expanding rollers and a mandrel for actuating the same, a frame having slots to receive said rollers and having a longitudinal bore to receive said mandrel, said frame also having a screw threaded outer end portion, a head screw threaded onto said outer end portion, having its outer end enlarged and having its inner end provided with a circumferential bearing surface, means for rigidly securing said head in adjusted positions on said frame, a collar rotatably mounted on the bearing surface of said head and arranged to engage the end of the tube, a thrust bearing interposed between said collar and the enlarged outer portion of said head, a guard screw threaded onto said collar, and extending beyond the inner end thereof to engage the tube sheet, and means for rigidly securing said guard in adjusted positions with relation to said collar.

In testimony whereof, I affix my signature hereto.

GUSTAV WIEDEKE.
